UNITED STATES PATENT OFFICE.

PAUL ROBERT G. SJÖSTRÖM, OF WESTFIELD, NEW JERSEY.

DESIGN FOR A GAME-BOARD.

SPECIFICATION forming part of Design No. 30,466, dated April 4, 1899.

Application filed March 11, 1899. Serial No. 708,766. Term of patent 7 years.

To all whom it may concern:

Be it known that I, PAUL ROBERT G. SJÖSTRÖM, of Westfield, in the county of Union and State of New Jersey, have invented and produced a new and original Design for a Game-Board, of which the following is a full, clear, and exact description.

Reference is to be had to the accompanying drawing, forming a part of this specification, in which the figure shown is a plan of a game-board embodying my design.

As shown in the drawing, the leading feature of the design consists in a base 1, upon which appears a rectangular figure 2, formed in double lines terminating in disks at the corners and also showing disks intermediate

of the corners, and from each corner-disk double lines extend toward the corners of the base. Within the rectangular figure 2 are four variously-disposed rectangular figures in the lines of which disk-like figures appear, and outside of the rectangular figures a number of angular figures appear, terminating in disk-like figures. The several disk-like figures are of various colors.

I claim—

The design for a game-board herein shown and described.

PAUL ROBERT G. SJÖSTRÖM.
